UNITED STATES PATENT OFFICE.

WILLIAM McCONWAY, OF PITTSBURG, PENNSYLVANIA.

CAR-COUPING.

SPECIFICATION forming part of Letters Patent No. 471,881, dated March 29, 1892.

Application filed February 8, 1892. Serial No. 420,696. (No model.)

To all whom it may concern.

Be it known that I, WILLIAM McCONWAY, a citizen of the United States, residing at Pittsburgh, in the county of Allegheny and State of Pennsylvania, have invented or discovered certain new and useful Improvements in Car-Couplers, of which improvements the following is a specification.

The invention described herein relates to certain improvements in car-couplers of the Janney or swinging-hook type, and has for its object a construction whereby a horizontally spring-actuated swinging locking-block may be employed, such having a bearing against the side of the coupler-head as against the thrust of the tail of the swinging hook; and it is a further object of said invention to provide a tripping device for said locking-block operative from either the upper or under side of the coupler, the locking-block and tripping device being so constructed and arranged with relation to each other that while the tripping device is always effective to shift the locking-block the movements of the locking-block when actuated by the tail of the swinging hook will not shift the tripping device, all as more fully hereinafter described and claimed.

In the accompanying drawings, forming a part of this specification, Figure 1 is a top plan view of one member of a coupler embodying my improvement. Fig. 2 is a sectional plan view of the same. Fig. 3 is a view, partly in side elevation and partly in section, the plane of section being indicated by the line xx ; Fig. 2. Fig. 4 is a transverse section on the line yy , Fig. 3. Fig. 5 is a plan view of the under side of a passenger-car coupler embodying my invention; and Fig. 6 is a sectional elevation, the plane of section being indicated by the line zz , Fig. 5.

In the practice of my invention a coupler-head 1 of the usual or any suitable construction is employed, and a hook 2, provided with a tail-piece 3, is so pivoted in said head that when the hook is swung into a closed position the tail-piece will move back into the head. As the tail-piece moves back into the head it pushes back a spring-actuated locking-block 4, which as soon as the tail-piece passes by is moved by its spring 5 in front of the tail-

piece, thereby locking the tail-piece and hook as against any outward movement. The locking-block 4 is arranged transversely of the coupler-head and is pivoted in such proximity to the side wall of the coupler-head that its rear end will have a bearing against such wall, which is provided with a recess for the rounded rear end of the locking-block. In this arrangement of the locking-block the longitudinal thrusts imparted to the locking-block by the tail-piece are transmitted to a very great degree to the side wall of the coupler-head, thus relieving the pivot-pin of the locking-block of excessive strain. The locking-block 5 is held in operative position by a spring 5, which bears at one end against the block at a point forward of the pivot-pin and at its rear end against bearing-plates 6, arranged in the stem of the coupler, the spring being in or approximately in the axial line of the coupler. These bearing-plates are made in two parts or sections, each section being provided with lugs 7, adapted to fit in suitable slots 8, formed in the side walls of the coupler-stem. 75 These plates are made of such dimensions that when placed together their combined width will be less than the internal width of the coupler by an amount approximately equal to the length of one of the lugs 7. In congregating the parts of the coupler the draft-bolt 9 is placed in position, then one of the bearing-plates is adjusted, and then the other bearing-plate is slid into line with the first plate and then pushed out laterally until its lug enters its slot 8. The spring 5, which is provided with a foot-piece 10 is then placed in position, the foot-piece entering the recess formed by the bearing-plates 6, thereby locking the bearing-plates in position. (See Figs. 2 and 3. 80

As shown in Fig. 2, the spring 5 holds the locking-block in such position that when the hook is closed the tail-piece 3 will bear against the free end of the block 4, thereby locking the tail-piece and hook in a closed position. In order to prevent a too great forward movement of the locking-block, stops or shoulders 15 and 16 are formed on the locking-block. The stop or shoulder 15 is formed on the front end of the block and adapted to 95 abut against the end of the tail-piece 3, as shown in Fig. 2, while the stop 16 is located

near the pivotal end of the locking-block, and is adapted to abut against a shoulder 17 on the side wall of the coupler. Either or both of these stops may be employed.

- 5 In order to shift the block 4 to permit of the outward movement of the hook, a lever 11 is pivoted on the coupler-head, and to said lever is attached a pin 12, which projects in through slot 13 in the coupler-head and engages the locking-block 4 in such manner that when shifted by its lever 11 it will move the locking-block out of engagement with the tail-piece 3, but will not itself be moved when the locking-block is shifted by the tail-piece 10 gages the locking-block 4 in such manner that when shifted by its lever 11 it will move the locking-block out of engagement with the tail-piece 3, but will not itself be moved when the locking-block is shifted by the tail-piece 15 moving back into the coupler-head. The relation of the pin and locking-block to each other may be effected in many ways—as, for example, by forming a recess 14 in the locking-block for the reception of the pin 12, said 20 recess extending from the point of entrance of the pin thereinto toward the front side of the block a distance at least equal to the rearward movement of the locking-block when shifted by the tail-piece 3.
- 25 When the coupler is to be applied to freight-cars, the lever 11 is so arranged, and the pin 12 is so connected thereto that a vertical movement of one end of the lever will shift the pin and the locking-block backward, as shown in 30 Figs. 1, 2, and 3, so that the hook may be unlocked by a vertically-moving arm on the end of the freight-car. As it is impracticable to place the mechanism for operating the locking-block on top of the coupler when applied 35 to passenger-cars, the slot 13 is formed in the under side of the coupler-head and the pin 13 passes up through said slot and enters the recess 14, which in this case is formed on the under side of the locking-block, as shown in 40 Figs. 5 and 6. The pin is shifted by a bell-crank lever 11 or any other suitable device which can be operated by a suitably-arranged lever on the platform of the car.

I claim herein as my invention—

- 45 1. In a car-coupler, the combination of a swinging hook provided with a tail-piece, a pivotal locking-block arranged transversely of the coupler-head and having a bearing at its pivotal end against the wall of the coupler, 50 and a spring bearing against the locking-block at a point intermediate between its pivotal point and its free end, substantially as set forth.

- 55 2. In a car-coupler, the combination of a hook provided with a tail-piece and pivoted on one side of the coupler-head, a locking-block pivoted on the opposite side of the coupler-head and extending transversely thereof, and a spring bearing against the locking-block at

a point intermediate between its pivotal point 60 and its free end, substantially as set forth.

3. In a car-coupler, the combination of a swinging hook provided with a tail-piece, a spring-actuated pivoted locking-block, and a movable pin arranged to shift the locking-block, but non-movable by the locking-block when shifted by the tail-piece of the hook, substantially as set forth.

4. In a car-coupler, the combination of a swinging hook provided with a tail-piece, a spring-actuated locking-block, and a vertically-movable pin for shifting the locking-block, substantially as set forth.

5. In a car-coupler, the combination of a swinging hook provided with a tail-piece, a spring-actuated locking-block arranged transversely of the coupler-head, and a lever pivoted to the head and provided with a pin projecting through a slot in the head and entering a recess 75 in the locking-block, substantially as set forth.

6. In a car-coupler, the combination of a hook provided with a tail-piece and pivoted on one side of the coupler-head, a locking-block pivoted on the opposite side of the coupling-head and extending transversely thereof, and a spring bearing at one end against the locking-block and at its opposite end against a suitable abutment in the stem of the coupler, substantially as set forth.

7. In a car-coupler, the combination of a swinging hook provided with a tail-piece, a locking-block arranged transversely of the coupler-head, sectional bearing-plates arranged in the stem of the coupler, and a spring interposed between the bearing-plates and the locking-block, substantially as set forth.

8. In a car-coupler, the combination of a swinging hook provided with a tail-piece, a spring-actuated pivoted locking-block arranged transversely of the coupler-head, and a stop or stops for limiting the forward movement of the locking-block, substantially as set forth.

9. In a car-coupler, the combination of a hook provided with a tail-piece and pivoted on one side of the coupler-head, and a spring-actuated locking-block pivoted on the opposite side of the coupler-head and extending transversely thereof and provided at its free end with a stop adapted to engage the end 105 of the tail-piece of the hook, substantially as set forth.

In testimony whereof I have hereunto set my hand.

WILLIAM McCONWAY.
